BACK REST AND PULL-OUT FOR SLIDING COUCHES

Samuel Weissman and Ralph Weissman,
Detroit, Mich.

Application November 1, 1935, Serial No. 47,780

1 Claim. (Cl. 5—18)

The present invention pertains to a novel back rest and pull-out for extension beds of the type commonly known as studio couches. A studio couch consists of a couch base enclosing a bed spring and slidably mounted over the same, the spring resting on the floor so that the couch base may be pulled out from the spring to form a bed of double width or completely detached from the bed spring to form twin beds. The couch base carries two pads or mattresses, one of which is loose and may be transferred to the bed spring to lie on the same level as the pad remaining on the couch base.

A studio couch is also equipped with a set of loose back cushions which are leaned against the wall, inasmuch as a studio couch ordinarily has no back rest. This feature is objectionable for several reasons. It is not always desirable to place the couch close to a wall, and in such a case, the back pillows must either be dispensed with or awkwardly placed, or the couch must be placed in other than the most desirable position.

Further, even if the couch is placed close to a wall, the position of the back pillows is such as to leave a large width between them and the forward edge of the couch, so that it is not comfortable for an occupant to recline against the back pillows, especially in the case of a short person.

Still another objection to the conventional studio couch is that the base cannot always easily be pulled away from the bed spring because of binding if the pull is in a slightly oblique direction or not exactly perpendicular to the length of the couch. The same difficulty occurs, to some extent, in pushing the couch base over the bed spring.

The object of the present invention is to overcome the aforementioned objections and is accomplished by the provision of a combined back rest and pull-out of original construction. This member is in the nature of a frame having a swivel connection to the end rails of the couch base. Thus, the seating width is shortened when the back pillows are placed against the back rest, it being understood that the actual width of the couch cannot be reduced without converting it to a less comfortable bed. In addition to the swivel attachment of the back rest, it may also have a sliding movement on or in the end rails until reaching a point near the forward ends of the rails. In this forward position, the back rest becomes a pull-out by means of which the couch base may be pulled away from the bed spring in

a straight line and in the proper direction so that there is no binding as stated above.

Finally, the back rest is adapted to be swung down against the forward side of the couch base and in such a manner as to lie entirely beneath the top of the end rails and for the most part beneath the top of the fixed pad on the couch base. In this position the back rest is entirely out of the way of a person lying on the couch base and also does not interfere with placing the bed sheets on the couch base or removing them. Moreover, the back rest in its suspended position is spaced from the floor sufficiently to permit foot room beneath it, which is also desirable in laying the bed sheets and removing them.

The invention is fully disclosed by way of example in the following description and in the accompanying drawings in which

Figure 1 is a perspective view of a studio couch having a combined back rest and pull-out according to the invention, one of the back pillows being removed for the purpose of illustration;

Figure 2 is an end view showing the back rest in use as a pull-out and the couch base partly pulled away from the bed spring;

Figure 3 is a similar view showing the couch base fully uncovering the bed spring and the pull-out in its suspended or idle position;

Figure 4 is a detail elevation showing the inner side of one of the end rails and the attachment of the back rest thereto;

Figure 5 is a section on the line 5—5 of Figure 4;

Figure 6 is an end view of a modified construction;

Figures 7 and 8 are end views of a modified construction, showing the back rest in different positions, and

Figure 9 is a detail elevation of the end rail, showing the slot.

Reference to these views will now be made by use of like characters which are employed to designate corresponding parts throughout.

In Figure 1 is illustrated a couch base 1 having feet 2 in its corners carrying rollers 3 on which the base is adapted to ride. The top of the base proper consists of a pad or mattress 4 resting on a concealed bed spring within the base and suitably upholstered as illustrated. Another bed spring 5 of conventional construction, resting on legs 6, stands on the floor and is normally concealed within the couch base. The couch base is adapted to be rolled from over the bed spring 5 as illustrated in Figures 2 and 3, these parts remaining either attached to each other as shown

or being separated from each other, if desired. This is the construction of the conventional studio couch. After the couch has been extended in this manner, a pad or mattress 7 lying loose on the pad 4 is transferred to the bed spring 5, as in Figure 3, whereby both pads are brought to the same level. The studio couch further includes three back pillows 8 which usually are reclined against the wall at which the couch is positioned.

As stated above, there are certain difficulties inherent in the placing of the back pillows on a backless couch and in the pulling of the couch base away from the stationary bed spring. The means for overcoming these difficulties, according to the present invention, will now be described. At each end of the couch base is secured an arm rest 9 or other suitable means for carrying end rails 10. These rails lie approximately in the plane of the loose pad 11 when it is superimposed on the fixed pad 4.

In the upper edge of each rail 10, near the rear end thereof, is cut a forwardly sloping notch or slot 11. The upper edge of each rail 10 is also notched near its forward end as indicated by the numeral 12 in Figures 1 and 2.

The back rest for the couch consists of an inverted U-shaped frame 13 with internal bracing and filling structure 14. The free ends of the frame 13 carry alined brackets 15 bent outwardly at 16 and again downwardly at 17 to extend into close proximity of the inner surfaces of the rails 10, respectively, as shown more clearly in Figure 5. Each end 17 carries a pin 18 extending through the corresponding slot 11 and formed with a head 19 disposed at the outer side of the rail to prevent the frame from readily detaching itself from the rail. Each rail 10 carries an inwardly extending fixed pin 20 behind the notch 11. The brackets 15, which are curved as shown in Figure 4, rest on the pins 20 when the pins 18 are in the rearward ends of the slots 11, whereupon the weight of the frame 13 binds the pins 18 against the upper edges of the slots. As shown in Figure 1, the back rest is adapted to support the back pillows 8 in a nearly upright position, and it is not necessary to place the couch against a wall for this purpose. Moreover, the seating or exposed width of the upper pad 7 is thereby reduced to a more comfortable dimension than when the pillows 8 are reclined against a wall.

In pulling the couch base to expose the bed spring 5, the operator first removes the pillows 8 in the usual manner. The top of the U-frame 13 is then grasped near its center by one or both hands and pulled forwardly. The initial pulling movement swings the frame on its pivots 18, and the continued pull draws the couch base from the bed spring 5, as shown in Figure 2.

When the couch base has been withdrawn as far as desired, the back rest is lifted to remove the ends 18 from their slots 11, and the pins are brought forwardly on the upper edges of the rails 10. The back rest is then drawn forwardly until the pins 18 are received in the notches 12, and the rest is finally swung downward to the position shown in Figure 3.

Because of the construction previously described, the back rest in its suspended position has no parts lying immediately over the pad 4 to interfere with the comfort of anyone lying thereon. Also, the frame 13 is of such height as to leave a clearance 21 above the floor, sufficient for the insertion of one's feet beneath the frame. This clearance is very desirable, for if the frame

13 reached the floor, the person laying the bed sheets or otherwise handling the couch would be likely to stub his toes against the frame.

In this connection, it is to be noted that the back rest and pull-out is conveniently disposed of after having served its purpose, without the necessity of being detached from the couch. Nevertheless, if it is desired to detach the back rest for any reason, it is readily removed from the notches 11 as previously described.

In the modification shown in Figure 6, each end rail 11' has a lengthwise slot 22 with upwardly rounded or enlarged ends 11' and 12' occupying respectively the relative positions of the notches 11 and 12 of Figure 1. The back rest frame 13' is constructed as previously described, and its end brackets 15' rest on fixed pins 20' carried by the rails 10', thereby lifting the headed pins 18' upwardly in the enlargement 11'.

In being drawn forward, the frame 13' rides along the slots 22 until reaching the forward enlargements 12' when it may be dropped to the position shown in Figure 3. In this position the frame may be detached from the rails, if desired, by successively removing the headed pins 18' from the enlargements 12', which is possible by slightly skewing the frame. This construction has the advantages of not requiring lifting of the frame before drawing it forward.

In the modification shown in Figures 7, 8 and 9, the frame of the back rest 30 is of inverted U-shape as in the previous constructions. From the base of the frame, at each end, as viewed in Figure 7 extends a leg 31 perpendicularly to the plane of the frame or towards the forward edge 35 of the couch. The length of this leg is approximately half the length of the end rail 32 or width of the couch base. The angle between the leg and the contiguous side of the frame is approximately 90°, for a purpose that will presently appear. At approximately the mid-point of each rail 32 the free end of the corresponding leg 31 is pivotally held by a bolt 33 and a thin nut 34 at the inner side of the rail. The bolt has a shoulder 33' engaging the outer side of the rail 45 so that the binding action of the bolt and nut is on the rail, leaving the leg free to swing. While in upright position, each leg 31 also rests upon a stud 36 carried by the corresponding rail 32 at a point rearward of the pivotal connection.

The couch base is drawn out by merely pulling the frame 30 forwardly in the manner described in connection with the previous constructions. The frame is then dropped to the position shown in Figure 7. When the frame is dropped, it assumes a position wherein the legs 31 and ends of the frame 30 lie alongside the upper end edges and forward vertical edges, respectively, of the couch base, due to the fact that the leg 31 is half the width of the rail 32 and pivoted at the mid-point thereof.

By reason of the bolt and nut construction described, the back rest may readily be removed if it is not wanted, by merely releasing the nuts.

Although specific embodiments of the invention have been illustrated and described, it will be understood that various alterations in the details of construction may be made without departing from the scope of the invention, as indicated by the appended claim.

What we claim is:

A studio couch having a main base and an inner base, the main base being adapted to be drawn forwardly to uncover the inner base, lower and upper seat cushions normally placed on the main

base, the upper cushion being adapted for use as a mattress for the inner base when the latter is uncovered, unitary end frames attached upon the outer ends of said main base and each having an upper transverse member serving as an arm rest and a transverse rail below said upper member and substantially on a level with the top of the upper cushion, a back having upright end portions and a longitudinal stretcher connected to said end portions, said back being of small height and disposed substantially entirely above the upper cushion, bracket arms, one at each end of the back, carrying the back and extending for-

wardly from the bottom thereof substantially along said rails and pivoted at their forward ends about midway between the ends of the rails to permit the back to be swung forwardly, whereby in an intermediate position it serves as a pull to draw the main base forwardly and in a lower forward position it lies wholly in front of, adjacent to and below the top of the lower cushion so as not to obstruct entrance at the front of the couch.
